Patented Aug. 9, 1927.

UNITED STATES PATENT OFFICE.

JOHN MCINTYRE, OF PORTOBELLO, EDINBURGH, SCOTLAND, ASSIGNOR OF ONE-HALF
TO SWINFEN BRAMLEY-MOORE, OF NEW YORK, N. Y.

GRINDING, REFINING, AND MIXING MACHINE.

Application filed December 6, 1926, Serial No. 153,011, and in Great Britain February 27, 1926.

The present invention relates to grinding, refining and mixing machines for grinding, refining and mixing cocoa beans, chocolate, chemicals and other similar substances, and 5 the invention aims to provide a novel and improved grinding element for such a machine, this invention being an improvement over the grinding elements disclosed in my Patent No. 1,564,427, granted Dec. 8, 1925. 10 A further object of the invention is the novel arrangement of rods on the face of a plate or blade, with provisions for the feeding of the material between the rods as the grinding element is moved within a cylinder 15 containing the material.

A further object is the provision of front and rear rods on the plate or blade and means for mounting said plate or blade so as to distribute and equalize the pressure 20 between the front and rear rods.

With the foregoing and other objects in view, which will be apparent as the description proceeds, the invention resides in the construction and arrangement of parts, as 25 hereinafter described and claimed, it being understood that changes can be made within the scope of what is claimed, without departing from the spirit of the invention.

The invention is illustrated in the accompanying drawing, wherein—

Figure 1 is a face or plan view of the complete grinding element.

Fig. 2 is a similar view of the plates or blades, with a portion of one plate broken away, and the rods and other parts removed.

Fig. 3 is a rear edge view of the grinding element.

Fig. 4 is an end view thereof.

Fig. 5 is a plan view of the keyplate.

Fig. 6 is an end view, with portions shown in section, showing the grinding elements attached to the rotor working within a cylinder.

In carrying out the invention there is provided a plate or blade 7 composed of suitable resilient sheet metal, and which is preferably elongated transversely of the line of movement thereof or parallel to the axis 50 around which the grinding element moves.

The blade 7 is carried by one or more blades or plates 8, also of resilient sheet metal. The plates 7 and 8 are secured together in spaced relation by means of rivets or other securing elements 9 extending along a line

longitudinally of the blade 7 substantially midway between the front and rear edges thereof.

Rods 10 are disposed on the face of the blade 7 and are spaced equidistant on either side of the longitudinal line of the rivets or studs 9. Each rod extends substantially one-half the length of the blade 7, with the rods disposed end to end, and the rods are preferably of circular cross-section, although 60 they may be of any suitable section. As shown, the rods are arranged in pairs forwardly and rearwardly of the longitudinal center line of the blade 7 along which the rivets 9 are disposed, although there may 65 be any number of such rods.

The rods 10 have their opposite and adjacent ends bent back inwardly to form the respective hooks 11 and 12. The hooks 11 engage over the ends of the blade 7, and said 70 blade has openings 13 intermediate its ends through which the hooks 12 are inserted. A keyplate 14 is slid across the inner surface of the blade 7 to enter the hooks 12, and has an open slot 15 to receive the bends of 75 said hooks, whereby said keyplate 14 will hold the inner ends of the rods in place 80 against the blade 7.

Bars 16 and 17 are secured in any suitable manner, such as by rivets, bolts or other suitable securing means, to the face of the blade 7 along the rear and front edges thereof, respectively, and contact with the rearmost and foremost rods 10 to assist in holding said rods in place. The front bar 90 17 has pins or fingers 18 projecting through apertures in the blade 7 and through apertures 19 in the keyplate 14, so that when the bar 17 is attached to the blade 7 it will 95 retain the keyplate 14 in place.

Lugs or studs 20 are secured on the face of the blade 7 between the rods 10 to space said rods apart and to maintain them in proper spaced relation on the face of the blade. The ends of the blade 7 also have 100 extensions 21 assisting in spacing the outer ends of the rods apart.

The blade 7 is provided between the rods 10 at suitable points with apertures or holes 105 22 through which the material may pass from the inner side of the blade 7 to the spaces between the rods 10.

As shown in Fig. 6, the blades or plates 8 are secured to an adjusting rocker 23 carried by a rotor 24 to serve as leaf springs trail- 110

ing from said rocker to press the blade 7 outwardly and hold the rods 10 against the inner surface 25 of the cylinder or casing in which the rotor operates, whereby the material is crushed or ground between the surface 25 and rods 10, as disclosed in the patent hereinbefore mentioned. The pressure of the blades 8 is transmitted through the rivets or studs 9 to the blade 7 intermediate the front and rear rods 10, to distribute the pressure to said front and rear rods substantially equally, and the blade 7 is bowed outwardly, as seen in Fig. 6, under the pressure received from the blades 8. This equalizes the pressure on the rods 10. Furthermore, the blades 8 extend across the apertures 22 at the inner side of and spaced from the blade 7, and during the forward movement of the grinding element, the material is forced between the blades 7 and 8, and is therefore forced outwardly through the apertures 22 between the rods 10, to be ground or refined.

Having thus described the invention, what is claimed as new is:—

1. A grinding element comprising a blade, and spaced rods secured on the face thereof to contact with a grinding surface, said blade having apertures between said rods for the flow of material through said apertures.
2. A grinding element comprising a resilient blade, front and rear rods secured on the face thereof, and resilient means connected to said blade between the front and rear rods to press the rods against a grinding surface.
3. A grinding element comprising a resilient blade, front and rear rods secured on the face thereof, and resilient means connected to said blade between the front and rear rods to press the rods against a grinding surface, said rods being spaced apart and the blade having apertures between said rods.
4. A grinding element comprising a resilient blade, front and rear rods secured on the face thereof, and a resilient blade connected to the firstnamed blade between the front and rear rods to press the rods against a grinding surface and spaced from the first named blade.
5. A grinding element comprising a resilient blade, front and rear rods secured on the face thereof, and a resilient blade connected to the firstnamed blade between the front and rear rods to press the rods against a grinding surface and spaced from the firstnamed blade, said rods being spaced apart, the firstnamed blade having apertures between said rods, and the secondnamed blade extending across said apertures to

force material which passes between the blades through said apertures.

6. A grinding element comprising a blade 65 having front and rear grinding portions, and a resilient blade connected to the firstnamed blade between the front and rear grinding portions, to press said portions against a grinding surface, the firstnamed 70 blade having apertures between said grinding portions, and the secondnamed blade extending across said apertures to force material which passes between the blades through said apertures.

7. A grinding element comprising a resilient blade having front and rear grinding portions, and resilient means connected to said blade at such a point as to apply pressure to said blade between the front and 80 rear grinding portions and thereby spring the blade and press said portions against a grinding surface.

8. A grinding element comprising a resilient blade having front and rear grinding 85 portions to bear against a grinding surface, and a resilient blade connected to the firstnamed blade at such a point as to apply pressure to the firstnamed blade between said front and rear portions toward said 90 grinding surface and thereby press said portions against said surface.

9. A grinding element comprising a sheet metal blade having spaced elongated grinding portions to bear against a grinding surface and follow one after the other in the movement of the blade along said surface with said portions disposed transversely of the line of movement of the blade, said blade having apertures between said portions for the flow of material through said apertures to pass in front of those grinding portions in rear of the apertures.

10. A grinding element comprising a blade having grinding portions thereon and 105 apertures for the flow of material therethrough to pass to said portions, and a resilient blade connected to the firstnamed blade for pressing said portions against a grinding surface, the secondnamed blade extending across said apertures to force material which passes between the blades through said apertures.

11. A grinding element comprising a blade having grinding portions at one side 115 thereof to bear against a grinding surface and having apertures for the flow of material through the blade to pass to said portions, and means at the opposite side of the blade arranged for forcing the material 120 through said apertures.

In testimony whereof I hereunto affix my signature.

JOHN McINTYRE.
